CAN OPENER

Jobby Belpedio, Bridgeport, Conn.

Application April 14, 1955, Serial No. 501,417

10 Claims. (Cl. 30—6.1)

The present invention relates to can openers, and particularly to a type for perforating the tops of beer cans and the like.

An object of the present invention is to provide an opener for perforating the top of a can at diametrically opposed points.

Another object is to provide an opener producing triangular-shaped perforations in which the points thereof are adjacent to the circumferential edge of the top, thereby permitting the contents to be poured or drunk without tending to spill.

Other objects include the provision of an opener of relatively simple and sturdy construction, and one which is easy and safe to use.

According to the present invention, a can opener is provided comprising a saddle portion for positioning on a can top, and opening lever means pivotally mounted on the saddle portion and comprising a long lever arm in the form of a handle portion and a pair of short lever arms carrying perforating means and projecting outwardly from the handle portion at its lower end. When the handle portion is rocked about its pivotal mounting, first in one direction and then the other, the said perforating means respectively engage and perforate the can top at diametrically opposed points.

Other objects and advantages of the invention will become apparent from a consideration of the following detailed description taken in connection with the accompanying drawings wherein satisfactory embodiments of the invention are shown. However, it will be understood that the invention is not limited to the details disclosed but includes all such variations and modifications as fall within the spirit of the invention and the scope of the appended claims.

In the drawings:

Fig. 1 is a front elevation of the opener of the present invention;

Fig. 2 is a side elevation thereof;

Fig. 3 is a top plan view, the dotted lines showing the position of a can engaged thereby;

Fig. 4 is a front elevation of the inner side of one of the half-sections of which the lever means of the invention is formed;

Fig. 5 is a side elevation of the half-section illustrated in Fig. 4, as seen from the right;

Fig. 6 is a top plan view of the half-section;

Fig. 7 is a front elevation showing in solid lines the lever member rocked in one direction, and showing it in dotted lines rocked in the other direction, the saddle member and top part of the can being shown in vertical section; and

Fig. 8 is a top plan view of the perforated can.

Referring to the drawings, an opener is provided comprising a saddle portion 10 having a substantially open bottom area 11, and a pair of upwardly extending arcuate parallel side walls 12 and 13 of such length as to exceed the diameter of the can the opener is designed to be used with, whereby the end edges of said side walls will

2

overhang the rim portion 14 of the can top 15. Connecting plates 16 and 17 join the said side walls at their overhanging ends. Lugs 18 and 19 depend from the opposing inside edges of connecting plates 16 and 17, 5 and are designed to engage the can directly beneath its top rim 14. The lugs are provided with inwardly curved edge portions 20 and 21 and substantially straight edge portions 22 and 23, the curved edge portions being in a circumferential line to fit about the wall of the can, 10 and the straight edge portions being tangential to such circumferential line at diametrically opposite points. The straight portions 22 and 23 of the lugs permit the saddle portion of the opener to be slipped laterally over the top of the can, while inwardly curved portions 20 and 21 embrace the cylindrical wall of the can to limit lateral movement of the saddle to a point where it straddles a diametric center line of the can top. In addition, to centering the saddle with respect to the can top, the presence of the lugs directly beneath the top rim 14 15 of the can anchors the saddle to the can top when the opener is in use.

Centrally disposed with respect to the lengths of the side walls and pivotally mounted therebetween on pivot pin 24, is an opening lever means generally designated as 25, comprising a normally vertical relatively long lever arm constituting a handle portion, generally designated as 26, having a pair of outwardly projecting relatively short lever arms 27 at its lower end, each having thereon a V-shaped blade portion 28 having a reinforcing rib 29 pressed upwardly therein. The distance between the two blades is such that their points will engage and perforate a can top at points adjacent to the inner edge of its rim. That is to say, the span between the outside ends of the blades is substantially equal to the diameter of the can top.

Positioned on opposite sides of the centrally positioned handle portion of the opening means, on upwardly extending arcuate parallel walls 12 and 13 of the saddle, are inwardly projecting indentations 30. These indentations control the amount of "play" in the handle portion of the opening means, and to some extent the size of the perforation made in the can top. Thus when the handle is rocked to one side causing the blade portion on that side to perforate the can top, the opposite blade portion will, after a limited upward movement, engage the indentation on its side of the wall 12 which stops its upward movement, thereby preventing any further downward movement of the handle and the perforating blade portion. The presence of the indentations also provides for safety in use, in that they prevent the blade portions of the opener from becoming exposed and thereby subjecting the user or his clothing to harm.

In operating the device, the saddle is slipped over the top of the can until the lugs 18 and 19 securely position it at a diametric center line of the can. Thereafter the handle is rocked first to one side and then to the other to produce diametrically opposed perforations at the inside edge of the rim of the can top. It will be noted that because of the blade portions of the opening means being V-shaped with the points thereof being directed outwardly from the handle, the point of the perforation will be adjacent to the inside edge of the rim, as opposed to the flat side of oppositely oriented V-shaped openings produced by the conventional rim engaging can openers where the rim is used as a fulcrum.

While the pivotally mounted opening means has been illustrated as having a pair of divergent blades, it should be understood that a similar handle with but one blade would, in some instances, have practical application. In such a case the saddle portion would be slipped over the can from one side thereof to make one perforation and would be removed from the top of the can and slipped

thereover from the other side for the purpose of making a diametrically opposed opening.

The opening lever is preferably hollow and formed of a pair of identical half sections of die-shaped sheet metal, one such section being shown in Figs. 4-6.

The half section illustrated comprises a handle-forming portion 31 having an inwardly extending flange along its top and sides, one half part 32 of this flange being substantially wider than the other half part 33, and being so dimensioned that the edge of the flange part 32 is at one side of the central vertical plane of the complete lever member and the edge of the flange part 33 is at the other side of said central vertical plane, the offset edges being connected by a transverse edge portion 34 at the top of the handle portion disposed along the center line of the lever member. The flange part 32 terminates in a bottom shoulder 35 extending inwardly to a lower side plate portion 36, while the flange part 33 terminates in line with a transverse shoulder 37 at the upper end of an outwardly and downwardly curved transverse wall portion 38 extending inwardly from one side edge of the plate portion 36 and upon the end of which there is provided the blade 28. The plate portion 36 is provided with a center hole 39 to receive the pivot pin 24, and its bottom edge is provided with a transversely extending lug 40 having its inner edge along the vertical center line of the half section. The edge 41 of the plate portion 36 opposite the transverse wall portion 38, is downwardly and outwardly curved in correspondence to the curvature of the outer surface of the wall portion 38.

In assembling the lever member, a pair of identical half-sections have their inner sides engaged with each other in interlocking relation, the edge of the flange part 32 of one half section fitting against the edge of the flange part 33 of the other half section, and the upper edge of the wall portion 38 of one half section fitting against the lower edge 35 of the flange part 32 of the other half section. The free side edge of the wall portion 38 of one half section abuts the inner surface of the plate portion 36 of the other half section adjacent the curved edge 41, and the transverse lug portion 40 of one half section abuts the transverse lug portion 40 of the other half section along the center line of the assembled structure, and its end portion overlies the lower edge of the plate portion 36. The two half sections are preferably rigidly secured together by spot welding at suitable contacting points, thus providing a rigid hollow lever member of relatively great strength, light in weight and which may be economically produced.

What is claimed is:

1. A can opener comprising a saddle portion for positioning on a can top, opening means pivotally mounted on said saddle portion at a point spaced substantially inward of the edge of said can top in the engaged relation of said saddle portion therewith, said means comprising a handle portion and perforating means projecting outwardly from the lower end of said handle portion in a direction away from said pivot point toward the edge of the can top, whereby when the handle is rocked on its pivot in the direction in which said perforating means projects therefrom the said can top is perforated by a cut made toward said pivot point and away from the edge of the can top.

2. A can opener comprising a saddle portion for positioning on a can top, opening means pivotally mounted on said saddle portion, said means comprising a handle portion and a pair of divergent perforating means projecting from the lower end of said handle portion, whereby when the handle is rocked to one side and then the other on its pivot the perforating means perforates the can at opposite points on the can top.

3. A can opener comprising a saddle portion for positioning on a can top, means for positioning said saddle portion at a diametric center line of a can top, opening means pivotally mounted on said saddle portion at a

point spaced substantially inward of the edge of said can top in the engaged relation of said saddle portion therewith, said means comprising a normally vertical handle portion and perforating means projecting outwardly from the lower end of said handle portion in a direction away from said pivot point toward the edge of the can top whereby when the handle is rocked on its pivot in the direction in which said perforating means projects therefrom the said can top is perforated by a cut made toward said pivot point and away from the edge of the can top.

4. A can opener comprising a saddle portion for positioning on a can top, means for positioning said saddle portion at a diametric center line of a can top, opening means pivotally mounted on said saddle portion, said means comprising a normally vertical handle portion and a pair of divergent perforating blade members projecting from the lower end of said handle portion, whereby when the handle is rocked to one side and then the other on its pivot the blade means perforates the can top at diametrically opposed points.

5. A can opener for beer cans and the like comprising a saddle portion having a substantially open underside, upwardly extending side walls, and means adjacent to its outer ends for mounting said saddle portion on a diametric center line of a can top, opening means pivotally mounted between the side walls of said saddle, said means comprising a handle portion and a pair of divergent perforating blades projecting from the lower end thereof, the span between the ends of the blades being substantially the same as the diameter of the can top, whereby when the handle is rocked to one side and then the other on its pivot the blades perforate the can top at diametrically opposed points thereof adjacent to the inside edge of the can rim.

6. A can opener for beer cans and the like, comprising a saddle portion having a substantially open underside, upwardly extending side walls, plates connecting said side walls at their outer ends, and means depending from said plates for engaging the saddle beneath the rim at the top of the can and for mounting said saddle portion on a diametric center line of the can top, opening means pivotally mounted between the side walls of the saddle centrally disposed with respect to the length of the side walls, said means comprising a normally vertical handle portion and a pair of divergent perforating blades projecting from the lower end thereof, the span between the ends of the blades being substantially the same as the diameter of the can top, whereby when the handle is rocked to one side and then the other on its pivot the blades perforate the can top at diametrically opposed points thereon adjacent to the inside edge of the can rim.

7. A can opener for opening beer cans and the like, comprising a saddle portion having a substantially open underside, upwardly extending arcuate parallel side walls, connecting means joining the side wall members at their outside ends, rim engaging lug means depending from the connecting means, said lug means having inwardly curved portions and substantially straight portions to thereby permit the saddle to be slipped laterally over the top of the can until the saddle straddles a diametric center line of the top, the inward curving portion of the lug means being positioned substantially on one side of the diametric center line and the straight portions being substantially on the other side thereof, an opener member pivotally mounted between the side walls of the saddle and centrally disposed with respect to the length of the side walls, said means comprising a normally vertical handle portion, and a pair of divergent blades projecting from the lower end of said handle portion within the area defined by the side walls, said opening means being such that when the handle portion thereof is rocked to one side on its pivot the outside edge of one blade will perforate the top of the can at a point adjacent to the inside edge of the rim and when rocked to the other side the other blade will perforate the top of the can

75

at a diametrically opposed point adjacent to the inside edge of the rim.

8. The opener according to claim 7, characterized by stop lugs projecting from the side walls of the saddle which limit the upward movement of one blade and the downward movement of the opposite blade.

9. An opener according to claim 7, characterized by V-shaped blades which produce perforations at diametrically opposed points on a can top in which the point of the V is adjacent to the rim of the can.

10. An opener according to claim 2, characterized in that said opening means comprises a pair of complemen-

tary interfitting joined hollow members, each having a handle forming portion at one side of the central vertical rocking plane of said opening means, and each having a can top perforating blade portion disposed one at one side of the pivot axis and one at the other side of said pivot axis.
